UNITED STATES PATENT OFFICE

2,542,110

TOBACCO TAMPER

Leonard W. Berchman, Los Angeles, Calif.

Application August 12, 1947, Serial No. 768,207

1 Claim. (Cl. 131—184)

1

The present invention relates to a tamper of a type which is adapted to be detachably secured to the bowl of a tobacco pipe and so positioned with relation to the bowl that any tobacco therein may be readily tamped.

An object of the invention is the provision of a tamper which is ornamental, which does not detract from the appearance of the pipe bowl and is so constructed as to permit the pipe bowl to be filled with tobacco without interfering with said filling.

A further object of the invention is the provision of a tobacco tamper for pipes which embodies in its construction a means whereby the pipe bowl may be readily cleaned of burnt tobacco.

A further object is the provision of a tobacco tamper which is inexpensive in cost of manufacture, of simple construction and superior to tobacco tampers now known to the inventor.

With the above mentioned and other objects in view, the invention consists in the novel and useful provision, formation, construction, association and relative arrangement of parts, members and features, all as shown in certain embodiments in the accompanying drawing, described generally and more particularly pointed out in the claim.

In the drawing:

Fig. 1 is a fragmentary side elevation of a pipe with its bowl, the bowl being shown partially in section, with the tobacco tamper of the invention shown mounted over said bowl;

Fig. 2 is a plan view of the tobacco tamper and looking in the direction of the arrow 2 of Fig. 1;

Fig. 3 is a fragmentary sectional view of the tobacco tamper on the line 3—3 of Fig. 2; and likewise showing a fragment of the pipe bowl in section;

Fig. 4 is a view similar to that of Fig. 3, with one of the tobacco tamper members in moved position from that of Fig. 3;

Fig. 5 is a fragmentary view, partly in section and showing one member of the tobacco tamper swung outwardly relative to the pipe bowl;

Fig. 6 is a plan view of a modified form of the device for securing the tamper to the pipe bowl; and

Fig. 7 is a side elevation of the tamper securing device shown in Fig. 6 and looking in the direction of the arrow 7 of said figure.

Referring now with particularity to the drawing:

The device of the invention in the embodiment shown in Figs. 1-5 inclusive includes a clip 1 having arms 2 and 3, interconnected by piece 4,

2

the arm 3 normally being positioned within the pipe bowl 5, while the arm 2 engages the exterior surface of the bowl at 6. As there is a difference in the external and internal surfaces of the bowl, the arm 3 is preferably made shorter than arm 2. Furthermore, the arm 2 is bowed at 7, and provided with a longitudinally extending slot 8. The connecting piece 4 is provided with two spaced apart and substantially parallel ears or lugs 9 and 10, between which is positioned arm 11. Arm 11 is adapted to be swingingly mounted between said lugs or ears in any convenient manner, although I preferably provide the arms or lugs at 12 and 13 with axially aligned, inwardly extending pivots, the said pivots being received within sockets 14 and 15 in the sides of the arm 11. Preferably the lugs are in frictional engagement with the sides of the arm 11, so as to require effort to move the said arm about its pivot points.

The arm 11 is formed with an elongated groove 16. The construction is such that there may be communication with said groove at one end of said arm, as shown at 17. It will be observed upon reference to Figs. 3 and 4 that the groove 16 is of variable depth, as for instance illustrated at 18, 19 and 20. The portion 18 of the arm is transversely bored at 21, and passed through said bore is an articulated member designated generally as 22. The articulated member is formed in two parts or stems 23 and 24, stem 24 being centrally secured to a foraminous disc 25. The stem 24 is provided with a bifurcated end to receive reduced end portion 26 of stem 23, the said stems being secured together by a pin 27 passed through aligned transverse bores in said ends. It will be observed upon reference to Fig. 3 that end 26 of stem 23 is at an angle and is adapted to engage complementary angled end 28 of the stem 24 when the stem 23 is moved to a vertical position, or from the position of Fig. 3 to that of Fig. 4. Preferably, the stems 23 and 24 are square in cross section and the transverse bore 21 is complementary thereto. This prevents rotation of the articulated member relative to arm 11. Surrounding stem 23 is a coil spring 29; one end of the spring bears against a head or finger piece 30 carried by stem 23, while the opposite end engages portion 18 of arm 11. The spring normally urges the articulated member in one direction to position the foraminous disc 25 adjacent the under surface of the arm 11, or in the full line position shown in Fig. 4. When the articulated member is fully extended, or in the position shown in Fig. 4, the stem 23 may be swung relative to its pivot point with the

3

stem 24, or to the position shown in Fig. 3, at which time the head or finger piece 30 lies adjacent one end of said arm. The end wall 31 of the arm 11 is curved slightly at 32 and in such a manner that when stem 23 is swung from the position of Fig. 4 to that of Fig. 3, the head or finger piece 30 will slide over said curved portion 32 and frictionally engage the end wall 31, and in this manner prevent the stem 23 from swinging to a vertical position under influence of the spring 29. When the stem 23 is lying in the horizontal position shown in Fig. 3, the spring 29 is under slight compression and constantly urges the stem 23 to move to a vertical position.

The form of the invention shown in Figs. 6 and 7 differs with respect to the means for securing the device to the pipe bowl. In place of providing a clip, I provide an interrupted ring 40 provided with out-turned lugs 41 and 42 at the interrupted portions of said ring, and with an intermediate offset portion 43 provided with a pair of spaced apart substantially parallel lugs 44 and 45. The lugs are provided with pivots 46 and 47. It is intended that the arm 11 with its associated parts should be positioned between pivots 46 and 47 in the same manner as said arm is positioned between the pivots of the lugs 9 and 10.

The operation, uses and advantages of the invention just described are as follows:

Assuming use of the invention of the form shown in Figs. 1-5 inclusive, the clip is passed over the bowl in the manner shown in Fig. 1, which will hold the device in position of service. The clip may be on the forward portion of the bowl or at any other location desired. The arm 11 may be swung from the position of Fig. 1 to that of Fig. 5 to permit the bowl to receive tobacco. Preferably the tobacco is simply poured from a tobacco pouch into the bowl without tamping the same with the finger. After the pipe bowl has been filled to a desired level with tobacco, the arm 11 is swung from the position of Fig. 5 to that of Fig. 1, whereupon the thumb may engage the head or finger piece 30 to flip the member 22 under spring actuation into an upright position or to the position shown in Fig. 4. The finger may then depress member 22 so as to force the disc 25 against the tobacco and in this manner the tobacco is tamped. After a tamping operation, the articulated member 23 is swung from the vertical position of Fig. 4 to that of Fig. 3 and the tobacco may then be ig-

4

nited for smoking purposes. The foraminous disc does not interfere with the burning of the tobacco and as a consequence the device may be left in the position shown in Figs. 1 and 3, or it may be swung to the position shown in Fig. 5. After the tobacco in the bowl of the pipe has been completely burnt, the clip may be removed from the bowl and the arm 2 used to scrape the interior of the bowl free of the burnt tobacco.

The form of the invention shown in Figs. 6 and 7 differs only as to the means for securing the device to the bowl; in this particular means it is clamped within the bowl, the pointed ends 49 engaging the interior of the bowl to prevent removal of the device, while the lugs 41, 42 and 43 limit downward movement of the device within the bowl. Other than this, the device as depicted in Figs. 1-5 remains the same.

Often during smoking the lighted tobacco within the pipe bowl requires tamping; obviously if the finger is used for this purpose it is liable to be burned. The present device solves this difficulty as tamping may occur at any time.

I claim:

A tobacco tamper, including an arm formed on one surface with an elongated groove and with a transverse bore communicating with the groove; a pair of stems hinged together, a disc carried by one of said stems and a coil spring surrounding the other stem and normally urging both stems in one direction relative to the arm to position the disc adjacent a surface of the arm, the said hinged relationship permitting swinging movement of one of the stems downwardly within the groove of the arm.
